ANIMAL GROOMING TABLE

Leonard Sciarrino, 6915 61st Road, Middle Village, N.Y.
11379, and Joseph Di Natale, 311 W. Drive, Copiaque,
N.Y. 11726

Filed June 29, 1970, Ser. No. 23,755

Term of patent 14 years

Int. Cl. D6—03

U.S. Cl. D33—14

FIG. 1

FIG. 2

FIG. 3

FIG. 4

FIG. 1 is a top plan view of an animal grooming table showing our new design;

FIG. 2 is a bottom plan view thereof;

FIG. 3 is a front elevational view thereof, the rear elevational view being similar; and

FIG. 4 is an end elevational view thereof, the showing being typical of the left and right sides.

We claim:

The ornamental design for an animal grooming table, substantially as shown and described.
